UNITED STATES PATENT OFFICE

HENRY CONRAD HEBIG, OF MIAMI, FLORIDA

DESIGN FOR A SPONGE-RUBBER SHOE

Application filed December 18, 1929. Serial No. 33,827. Term of patent 7 years.

To all whom it may concern:

Be it known that I, HENRY CONRAD HEBIG, a citizen of the United States, and a resident of Miami, county of Dade, and State of Florida, have invented a new, original, and ornamental Design for a Sponge-Rubber Shoe, of which the following is a specification, reference being had to the accompanying drawing, forming a part thereof.

Referring to the annexed sheet of drawings,

I claim:

The ornamental design for a sponge rubber shoe, as shown.

HENRY CONRAD HEBIG.
